CLAIM

The ornamental design for a door lever, as shown and described.

DESCRIPTION

FIG. 1 is a front perspective view of a door lever showing the design according to a first embodiment;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front perspective view of a door lever showing the design according to a second embodiment;

FIG. 9 is a front view thereof;

FIG. 10 is a rear view thereof;

FIG. 11 is a top view thereof;

FIG. 12 is a bottom view thereof;

FIG. 13 is a left side view thereof;

FIG. 14 is a right side view thereof;

FIG. 15 is a front perspective view of a door lever showing the design according to a third embodiment;

FIG. 16 is a front view thereof;

FIG. 17 is a rear view thereof;

FIG. 18 is a top view thereof;

FIG. 19 is a bottom view thereof;

FIG. 20 is a left side view thereof; and,

FIG. 21 is a right side view thereof.

The broken lines shown represent portions of the door lever that form no part of the claimed design.

(Continued)

Shading is used in the drawings to better illustrate the design.
